Atty.

UNITED STATES PATENT OFFICE.

WALDO G. GERNANDT, OF CHICAGO, ILLINOIS, ASSIGNOR TO GERNANDT MOTOR CORPORATION, OF CHICAGO, ILLINOIS, A CORPORATION OF ILLINOIS.

HIGH-PRESSURE COMBUSTION-ENGINE.

1,361,044.

Specification of Letters Patent.

Patented Dec. 7, 1920.

Application filed June 26, 1918. Serial No. 241,986.

To all whom it may concern:

Be it known that I, WALDO G. GERNANDT, a citizen of the United States, and a resident of Chicago, in the county of Cook and State 5 of Illinois, have invented certain new and useful Improvements in High-Pressure Combustion-Engines, of which the following, when taken in connection with the drawings accompanying and forming a part 10 hereof, is a specification sufficient to enable those skilled in the art to make and use the same.

This invention relates to a combustion engine which does not require an ignition plug 15 or spark, to ignite the fuel mixture contained in the combustion chamber of the engine; and which does not require a carburetor to obtain a suitable fuel mixture of a hydrocarbon liquid and air.

20 The objects of the invention are to obtain an engine of the kind named which is simple in construction and certain in operation; which contains few parts and not liable to break or get out of order; to obtain an economically made engine and one which is durable; and to obtain an engine which is easily understood and operated.

Additional objects are disclosed by the specification and claims.

30 I have illustrated the invention set forth herein as embodied in a construction applied to a two cycle internal combustion engine, and in the drawings.

Figure 1 is a vertical section, in ignition 35 position, and

Fig. 2 a like vertical section in position immediately prior or subsequent to ignition.

A reference character applied to designate a given part is applied to said part wherever 40 the same appears throughout the several figures of the drawings.

Crank shafts driven by a connecting rod from a piston, and cam shafts adapted to unseat valves being common to reciprocating 45 combustion engines I have not illustrated either the crank shaft, the cam shaft or the connections from the cam shaft to the valve in the drawings forming a part hereof.

A represents a piston which is provided 50 with recess α and rings α' , and is longitudinally movable in cylinder B. b represents the water cooling chamber of the engine; and C, the connection rod one end whereof

is attached to piston A by the pin D. E represents the air inlet to cylinder B and F 55 the exhaust or outlet from said cylinder. G represents the combined compression and combustion chamber of the engine. H represents the head of cylinder B, and is secured thereto by bolts (h) with the ordinary 60 packing (I) interposed between said head and the end of said cylinder. The head H is represented as water cooled, h' being the water cooling chamber thereof. J, j represents a fuel depository of two diameters. 65 Portion j of the fuel depository is contained in the plug K, which is provided with external screw threads k which fit a correspondingly screw threaded recess in head H; and is also provided with the radially ex- 70 tending passageways k' which constitute means for continuous connection between chambers G and J. j. K' indicates packing material which is interposed between plug K and the head H before said plug is secured in position. The packing is to make sure that the only connection between said combustion and fuel depository chambers is by way of said apertures k'. L represents a 75 plunger which is mounted to move longitudinally in portion J of fuel depository J. j. l represents a shoulder on plunger L, which forms a valve co-acting with valve seat m. Said valve is normally seated on said seat in the operation of the engine. M represents a 80 gland on plunger L; M' being the packing in said gland. N represents the lower end of a fuel supply pipe or conduit which at its receiving end is in communication with a source of fuel supply under pressure. n 85 represents a union by means of which the lower end of pipe or conduit N is joined to the plug, lettered O. Plug O is provided with external screw threads at both ends; the threads on the lower end thereof fitting 90 in corresponding threads in a circular recess in head H. O' represents packing material which is interposed between said plug O and the external face of head H before said plug is, by means of said screw threads, rigidly 95 secured to said head. P represents a passageway through the plug O, which communicates at its upper end with pipe or conduit N, and at its lower end is provided with the ball check valve p. p' indicates a pin 100 105 which limits the movement of check valve p.

Q represents a passageway which is in continuous communication at its lower end with fuel depository J j and, when check valve p is unseated, is in communication at its upper end with passageway P.

The cam on the cam shaft of the engine is connected to the plunger L, in the ordinary way, to actuate said plunger and said cam is set in timed relation with the crank shaft 10 of the engine to hold the shoulder l normally closed on seat m, to insure no leakage from the upper end of the fuel depository through packing M'. Said cams are also so shaped and set, in timed relation to the crank of the 15 engine that as piston A approaches and is near to the limit of its upward travel plunger L is forced downward in portion J of fuel depository J j.

The fuel depository being, as hereinbefore 20 described, at all times in communication with the combustion chamber G of the engine a substantially equal pressure obtains in said fuel depository and in said combustion chamber, when the plunger L being in 25 its normal position, with shoulder l seated. When, however, plunger L is forced downward its rate of travel being faster than the travel of piston A, the pressure in the fuel depository is thereby increased to above the 30 pressure in said combustion chamber, and fuel contained in said depository, (at the lower end thereof), is forced therefrom through passageways k' into said combustion chamber. Upon said forcing of said 35 fuel into said combustion chamber, the air contained therein being under pressure and by the rapid creation of said pressure, (as well as by the high temperature of the cylinder B caused by previous combustions), being 40 at a high temperature, ignition thereof will occur, and quick combustion thereof will follow; thereby forcing the piston A downward and actuating the engine.

The descent of the plunger L, where but 45 little fuel is contained in the fuel depository, will force all said fuel into said combustion chamber prior to any considerable downward movement of piston A, particularly where an extremely rapid downward 50 movement of said plunger occurs. Where the movement of said plunger is not so rapid as last above indicated and the quantity of fuel in said depository is greater than above suggested what may be termed a continuous 55 combustion during considerable movement of piston A occurs. The pressure of combustion in the combustion chamber may thus be maintained during an appreciable travel of said piston.

60 The operation of the engine is:—Fuel in a liquid form flows down supply pipe N from a source of supply under pressure, and flowing by the check valve p through the passageway Q falls into fuel depository J j 65 where, by gravity, it falls to the bottom of

the portion j of said fuel depository, adjacent to the inner ends of the radially extending passageways k'.

The relative length and diameter of these passageways k' being such that a greater 70 pressure at the inlet end thereof than at the outlet end is required to force a flow of said fuel therethrough, the fuel will remain in said lower end of said depository until the movement of the plunger L downward from 75 its normal position, as illustrated in Fig. 1 to its position as illustrated in Fig. 2 occurs.

The downward movement of said plunger L is timed relative to the movement of piston A so that said plunger L commences its 80 downward movement at substantially the same time said piston arrives at and is ready to commence its downward movement, the pressure in the combustion chamber of the engine and in said depository being at said 85 time substantially the same. The rate of travel of said plunger, being considerably faster than the rate of travel at said time of said piston, the pressure of the contents of the fuel depository J j, is increased to 90 above the pressure of the contents of the combustion chamber G and said contents including the fuel in said depository are forced through said radial passageway into the combustion chamber and into the air 95 under pressure therein.

Combustion occurs on the entrance of said fuel into said combustion chamber and said combustion is continuous until the maximum quantity of fuel which can be burned 100 by the quantity of air in said chamber is injected thereinto.

The downward movement of said plunger in the above recited operation may vary in speed, thereby varying the time during 105 which combustion continues in the combustion chamber of the engine. On the slower relative travel of said plunger a less initial ignition pressure occurs in the combustion chamber than on a rapid movement of said 110 plunger, relative to the movement of the piston; but the combustion being longer continued the ignition pressure is correspondingly longer continued in said combustion chamber.

By igniting fuel in the combustion chamber as the piston passes over the dead center and continuing the said ignition by supplying additional fuel in the manner last above recited, the maximum pressure in the combustion chamber is maintained to the time the piston has descended until the slippage angle of the crank shaft has been passed.

Particular attention is called to the position of the passageways k' relative to the 125 upper end of the piston A at the time said piston is at the limit of its inward travel, that is, toward the combustion chamber, said position being illustrated in Fig. 1. The lower end of the plug K entering re- 130

cess *a*, at said time, the radial discharge of fuel, from said passageways is close to the upper end of said piston and hence ignition will first occur adjacent to the piston, and 5 from thence will spread upward, or remains stationary as piston *A* descends. The cushion afforded by the combustion commencing, as above recited, adjacent to the cylinder head, tends to lessen the shock incident thereto in the combustion chamber. 10 The piston being in motion on the power travel thereof before all the combustion which occurs in said chamber is completed, is an additional beneficial condition in a 15 high pressure combustion engine.

I claim:

1. In an engine, provided with a combustion chamber, a fuel depository, having two diameters, a plug in the lower portion of 20 said depository, said plug provided with a central hollow portion which forms the part of the fuel depository of lesser diameter and with radially extending passageways in continuous communication with said 25 depository and with the combustion chamber, and means to supply fuel to said depository, in combination with means, comprising a longitudinally movable plunger positioned in the part of said depository, of 30 larger diameter, to force the contents of said depository, including said fuel, through said radially extending passageways into said combustion chamber.
2. In an engine, provided with a combustion chamber, a fuel depository, having two 35 diameters, a plug in the lower portion of said depository, said plug provided with a central hollow portion which forms the

part of the fuel depository of lesser diameter, and with radially extending passageways in continuous communication with said depository and with the combustion chamber, and means to supply fuel to said depository, in combination with means, comprising a longitudinally movable plunger 40 positioned in the part of said depository of larger diameter, to force the contents of said depository, including said fuel, through said radially extending passageways into said combustion chamber, said plunger provided 45 with a shoulder, and a valve seat adapted to 50 co-act with said shoulder.

3. In an engine provided with a combustion chamber, a fuel depository, means, comprising a fuel supply pipe, a check valve 55 thereto, and a passageway therefrom to said depository, to supply fuel to said depository, and radially extending passageways in continuous communication with said combustion chamber and said depository, said passageways of small diameter to obstruct, the pressure being equal in said depository and chamber, flow of fuel therethrough, in combination with means comprising a valve seat, a plunger longitudinally movable and a 60 shoulder on said plunger arranged to co-act with said seat, said plunger when advanced adapted to increase the pressure in said depository, to force fuel through said passageways and into said combustion chamber, and 65 when retracted to seat said shoulder.

WALDO G. GERNANDT.

In the presence of—

CHARLES TURNER BROWN,
J. SCUDDER.
